BOX STRAPPING MACHINE

Frederick M. Byl, San Jose, Calif.

Application May 10, 1937, Serial No. 141,654

17 Claims. (Cl. 100—31)

The present invention relates to improvements in box strapping machines and its principal object is to provide a machine of the character described which is simple in construction, speedy in 5 operation, economic in use and which performs its operation while the box remains stationary so as to prevent any shaking or jarring of any perishables that may be contained in the box.

More particularly my invention is intended 10 principally for use in connection with boxes used in fruit packing houses. Boxes of this kind, in addition to being nailed, are usually strapped near their outer ends, and this operation when done by hand or machinery available at the present 15 time is quite laborious and usually involves the turning of the box which is detrimental to the fruit or vegetables contained therein.

It is proposed in the present invention to provide a box strapping machine in which a wire is 20 strapped around the end of the box while the latter is in a position of rest.

It is further proposed to provide a machine of 25 the character described in which both ends of the box may be strapped at the same time for doubling the speed of the operation.

It is further proposed to provide a novel mechanical movement for accomplishing the objects set forth.

It is further proposed to arrange the box 30 strapping means in such a manner that the machine may be adjusted readily for different sizes of boxes by the mere exchange of an easily accessible guide plate.

Further objects and advantages of my invention 35 will appear as the specification proceeds.

The preferred form of my invention is illustrated in the accompanying drawings in which

Figure 1 shows a side view of my box strapping machine;

Figure 2 a vertical section taken along line 2—2 40 of Figure 1;

Figure 3 a plan view of a portion of the machine as seen from line 3—3 of Figure 1;

Figure 4 an enlarged detail view of a cam plate 45 used in my machine;

Figure 5 a vertical section similar to that of Figure 2, but showing certain parts in a different position;

Figure 6 a vertical section through a wire feed 50 mechanism;

Figure 7 a plan view of the wire feed mechanism;

Figure 8 a perspective detail view of a wire holder used in my machine;

Figure 9 a perspective view showing one end of

a box to which the wire has been applied so as to be ready for the final twisting or tying operation, and

Figure 10 a section taken along line 10—10 of Figure 1.

While I have shown only the preferred form of my invention I wish to have it understood that various changes or modifications may be made within the scope of the claims hereto attached without departing from the spirit of the invention.

Referring to the drawings in detail, I provide a platform 1, suitably supported by means not shown, the platform comprising a front section 2 having a plurality of balls 3 partly imbedded therein and a main section 4 which has rollers 5 secured to the edge thereof, the top edges of the rollers being in a plane with the top faces of the balls.

The box 10 to be strapped is placed by the 20 operator or by suitable machinery, upon the front section 2 of the platform and is pushed along on the balls and the rollers until it reaches the stops 6, when it is in proper position for the strapping operation. When thus positioned, both ends of 25 the box project beyond the rollers 5, as shown with respect to one end in Figure 2. Throughout this description it should be understood that the means shown and described for strapping one end of the box may be readily duplicated for 30 strapping both ends at the same time.

The strapping mechanism is supported by a vertical plate 7 which latter is arranged parallel and in spaced relation to the edge of the platform or the rollers 5, as shown in Figure 2, and is supported by any suitable means not shown in the drawings. It carries upon its outer face (see Figure 1) a wire feeding mechanism and upon its inner face a wire attaching mechanism (see particularly Figures 2 and 5) and a wire twisting 40 mechanism, which latter does not form any part of the present invention and therefore is not shown or described.

The wire feeding mechanism is shown in its principal features in Figure 1 and in detail features in Figures 3, 4, 6, 7, and 10. It comprises essentially an extensible guide rod 11 pivoted to the plate 7 as at 12 and carrying at its upper end a feed spout 13, an operating mechanism 14 for the guide rod, and a guide plate 15.

The guide rod 11 is made in two parts 16 and 17, the latter being slidable longitudinally in the former and projecting beyond the upper end thereof. In its upper end part 17 carries the wire spout 13 (see Figure 6) which is mounted in bear- 50 55

ings 18 adapted to be adjusted by a nut 19. The spout has a disc 20 secured upon its outer end by means of a nut 21 and this disc has a flat section 22 in its circumference. A spring-pressed plunger 23 bearing on the flat section has a tendency to hold the disc and the spout against rotation when the spout occupies a horizontal position as in Figure 1. The plunger, however, yields to permit rotary motion when sufficient force is applied.

10 A wire 25 is passed from a spool (not shown) through suitable stretching means (not shown) and through a positive arresting means 26 into a guide tube 27 and thence through an aperture 28 in the spout for feeding from the turned discharge end of the latter. The spout is intended to travel around the projecting end of the box 10, starting along the bottom and following the dotted line shown in Figure 1. While it travels it feeds the wire around the box and automatically turns in its bearings as it passes each corner of the box.

To cause the feed spout to follow the course outlined I provide the operating mechanism 14 in combination with the guide plate 15. The operating mechanism comprises a lever 30 pivoted to the plate 7 as at 31, the pivot being spaced from the upper end of the guide rod 11 by a considerable distance as shown in the drawings. One arm 32 of the lever is connected to part 16 of the guide rod 11 by means of a link 33 and the other arm of the lever is connected to the upper end of part 17 of the guide rod by means of a link 35.

The link 33 is made extensible and consists of a cylinder 36 pivoted to the arm 32 as at 37, a piston 38 movable in the cylinder and a piston rod 39 pivoted to part 16 of the guide rod as at 40. The link may thus be contracted and extended by feeding a pressure medium on one side 40 of the piston while exhausting from the other side, for which purpose a suitable four way valve 41 of conventional type may be used. It will be noted that when pressure is admitted for extending link 33 it has a tendency to move part 45 16 of guide rod 11 to the left (as viewed in Figure 1) and part 17 of the guide rod in an upward direction, while contraction of link 33 has a tendency to pull part 16 of the guide rod to the right and part 17 in a downward direction.

50 For guiding the guide rod 11 to cause the wire feed spout to follow the desired course, I provide the guide plate 15 which is removably and exchangeably secured to the plate 7 behind the guide rod 11. The guide plate is formed with a 55 cam groove 42 which is used for guiding a pin 43 projecting from part 17 of the guide rod 11 through a longitudinal slot 44 in part 16 into the groove, and the latter is formed to guide the member 17 for causing the feed spout to take the desired path around the box.

The shape of the cam groove does not exactly register with that of the box and is preferably made as shown in Figure 4. The bottom portion 65 45 is preferably formed on a slight curve which has a tendency to smooth out the angle between it and the sides 46 and 47 of the groove, which are made slightly slanting for the same purpose. This facilitates travel of the pin 43 around the lower corners.

70 The upper portion 48 of the groove may be slightly curved in an opposite direction, as it is important that near the juncture indicated at 49 the groove be drawn substantially to the arc of a circle having the pivot 12 of the guide rod 75 for its center so that there will be no slack in the

wire fed while the spout passes from point 50 indicated in Figure 1 to the nearest corner of the box. It should be understood that sufficient resistance is provided to the feeding of the wire to prevent any slack as long as the spout keeps 5 the wire already fed in a taut condition.

An initial fastening means for the wire is provided in the post 51 which is shown in detail in Figure 8 and which is circular in cross-section and terminates, in its upper end, in a semi-cylindrical extension 52 having a longitudinal slot dividing the same in a pair of spaced prongs 53 and 54, the spacing between the prongs corresponding substantially to the thickness of the wire to be used.

This post 51 is mounted rearwardly of the plate 7 in a bracket 55 and with freedom of sliding motion in a vertical direction. A spring 56 bearing on a pin 57 projecting from the post normally holds the latter in its uppermost position, that is with the prongs almost touching the box. The lower end of the post is received in a cylindrical socket 58 at the upper end of a piston rod 59 which latter projects from a piston 60 movable in a cylinder 61. Movement 20 may be imparted to the piston in either direction by a pressure medium under control of a suitable combination intake and exhaust valve indicated at 61'.

The socket 58 has a pin 62 riding in a spiral groove 63 of the post for turning the latter through an angle of 180 degrees when the socket moves endwise, the latter being held against turning movement by a pin 64 riding in a vertical groove 65 in the supporting bracket 55.

The post is thus mounted with freedom of turning movement between the positions shown in Figures 2 and 5 respectively. In the position shown in Figure 2 the two prongs clear the path of the wire feed spout so that the latter may pass 40 freely, while in the position shown in Figure 5 the slot between the prongs lies directly in the path of the wire and the prongs are used as a point of attachment for the wire at the beginning of each strapping operation.

The wire is fastened to the post in the following manner: Figure 1 shows the operating parts substantially at the end of a wrapping operation. During the operation just finished the end of the wire was attached to the post, the spout 50 guided around the box and past the post to parallel itself on the left side of the post so that at the moment indicated there are two strands of wire in substantially parallel and adjacent relation between the post and the spout, ready for a 55 tying or twisting operation not disclosed in the present application. The post, during the latter part of the operation, was in the position shown in Figure 2 so as to allow the spout to pass. The pin 43 at this time is in the left hand lower 60 corner of the cam groove, substantially as shown in both Figures 1 and 4.

The next operation would be the twisting of the parallel strands between the post and the spout and the cutting of the wire at the post and at 65 the spout. But for the starting of the next operation it is desirable that a portion of wire remains projecting from the spout, and to take care of this, the pin 43, instead of stopping at the lower left hand corner of the cam groove, is permitted to continue its travel into a dead end continuation 66 of the groove.

This dead end is normally closed by a pawl 67 pivoted to the plate 15 as at 68, but the pawl is operated, at this particular time, by any suit-

able means, to open the dead end and close the bottom end of the upright portion 45 of the cam groove so that the pin 43 may enter the dead end. The movement of the pawl 67 is transmitted, 5 through the link 69, the lever 70 and a spring-pressed rod 71 to the wire arresting means 26 which is operated to arrest further feeding of the wire so that the extended travel of the pin 43 into the dead end 66 effects a tightening of the 10 entire wire around the box.

While the pin 43 moves toward the limit of the dead end groove, the twisting and cutting action takes place, with the result that the wire is 15 tightly fitted around the box and that a piece of 15 wire remains projecting from the spout.

For the beginning of the next operation the post 51 is turned, by operation of the piston 60, through an angle of 180 degrees so that the slot between the prongs lies now in alinement with 20 the piece of wire projecting from the spout. The latter is now made to travel backward, by operation of the piston 38, so as to cause the pin 43 to re-enter from the dead end into the bottom portion 45 of the cam groove and to cause the 25 end of the wire projecting from the spout to enter the slot between the prongs which latter are preferably rounded at the point of entry, as at 72, to facilitate the engagement. As soon as 30 the wire has entered, the post is turned to bind the end of the wire and to clear the path for the spout when it passes the post on its return from the next trip around the box.

While the pin 43 moves backward in the bottom groove for connecting the wire to the post, 35 the position of the pawl 67 is changed to close the dead end and to open the vertical groove 46. The backward movement of the pin 43 in the groove 45 is limited by a spring-operated pawl 73 which prevents further backward movement 40 but allows movement in the opposite direction. Two similar spring-operated pawls 74 and 75 are provided at opposite corners of the cam groove to positively guide the pin 43 into the proper direction at these points.

45 The bracket 55 has a fixed collar 76 surrounding the upper portion of the post 51 and this collar has a slanting upper end as shown at 77. As has been previously pointed out, the piston 60, in addition to effecting a turning movement 50 of the post through the pin 62, may also be used for retracting the post against the opposition of the spring 56, and this retractive movement is used, between any two operations, for clearing the post of the remnant of wire adhering thereto from the previous operation.

55 The entire operation may be described as follows: At the start of the operation, the guide pin 42 may be considered as being in the extreme end of the dead end 66, with the pawl 67 in the dotted line position of Figure 4, a piece of wire projecting from the end of the spout 13, as shown in Figure 7, the spout being yieldingly held in horizontal position by the plunger 23 and the post turned to bring the slot into alinement with the projecting wire.

60 A pressure medium is now admitted into the cylinder 36, on the left side as viewed in Figure 1, whereby the guide rod with the spout is moved to the right, the pin 43 riding out of the dead end into the bottom portion 45 of the groove until it is stopped by the pawl 73. During this 65 movement of the spout the free end of the projecting wire is introduced between the prongs of the post 51 (see Figure 7), which at this time, occupies the position indicated in Figure 5.

Next a pressure medium is admitted into the cylinder 36, underneath the piston 60, whereby the latter is moved upward, causing the pin 62 to ride upward in the spiral groove 63 and to turn the post by 180 degrees, that is, into the position shown in Figures 2 and 3, whereby the wire is substantially locked to the post. 5

In timed relation to this last movement the pawl 67 is moved into the full line position of Figure 4 which also causes the feed arresting means 26 to be released so that the wire is now free to feed through the spout. 10

Now the pressure medium is admitted into the cylinder 36 on the right side of the piston 38 (see Figure 1) whereby the guide rod is made to swing to the left due to the action of the link 33, until the pin 43 strikes the pawl 67. At this time further progress to the left is prevented and further extension of the link 33 causes the lever 30 to swing about its pivot and to exert upward pressure on the link 35 which causes the upper part 17 of the guide rod 11 to slide upward, the pin 43 riding in the groove 46 and causing the spout which turns on its bearings as it turns around the corner of the box, to follow the dotted line indicated in Figure 1, until it reaches the point 59. At that time the pin 43 has reached the top of the groove 46 and has passed the pawl 75 which prevents a return movement. The spout, of course, keeps feeding out the wire as it 20 advances. 25

Next the pressure medium is applied to the left hand side of piston 38 (Figure 1) causing the link 33 to contract and to pull the guide rod to the right, causing the spout to pass over the top of the box to the right hand side until the pin 43 reaches the right end of the upper groove 48. Further contraction of the link 33 causes the lever 30 to swing about its pivot and to exert downward pull on the part 17 of the guide rod 11 so as to cause the spout to travel downward along the right side of the box as shown in dotted lines in Figure 1. The pin 43 in the mean time travels downward in the groove section 47 until it passes the pawl 74. 30 35

It should be noted that although the spout follows the dotted line path which is longer than the circumference of the box, the length of wire actually fed through the spout is exactly that called for by the dimensions of the box since 40 there is enough resistance to the wire to stop feeding when no wire is required. Thus no wire will be fed while the spout moves from point 59 to the nearest edge of the box and the feed is slowed down while the spout moves down the 45 right side of the box. 50 55

After the pin 43 has reached the lower right hand corner of the cam groove, the pressure medium in the cylinder 36 is again changed to urge the guide rod 11 to the left. The pin 43 60 freely passes the pawl 73 and as it approaches the left end of the bottom groove the pawl 67 swings into the dotted line position of Figure 4, tightening the arresting means 26 upon the wire and permitting the pin 43 to enter the dead end 65 of the groove. As it passes to the limit of the dead end groove it effects a final tightening of the wire that has been fed around the box and as a result of this operation two strands of the wire are arranged in parallel and adjacent relation between the post and the spout, substantially 70 as shown in the perspective view of Figure 9.

These two strands are now twisted together by means of a conventional twisting mechanism not shown in the drawings, which latter also cuts the 75

wire on opposite sides of the twist, that is, at a point adjacent the post and at a point spaced from the end of the spout so as to leave a short piece of wire projecting from the spout for the beginning of the next operation.

5. A pressure medium is now admitted above the piston 60 in the cylinder 61 for pushing the piston clear down, whereby the post is turned to its initial position with the slot in line with the piece 10 of wire projecting from the spout. This operation also causes the post to momentarily retract below the member 77 for ejecting the remnant of the wire still adhering to the post. The spring 56 returns the post to operative position when 15 the pressure is released so that the different parts are now in position for the next operation.

The finished box is now removed, preferably by withdrawing the stops 6, which may be made retractile, and a new box is substituted.

20. It will be noted that the path described by the wire feeding spout is determined by the shape of the groove in the plate 15 and that the apparatus may be easily changed to strap a box of different shape by the mere substitution of a 25 different cam plate.

I claim:

1. In combination, an extensible member, means for swingably supporting one end thereof, means for moving the member to cause its free 30 end to describe the path of a loop, the latter means comprising means for alternating swinging effects with extension and contraction effects and guide means controlling the duration of the effects, and means for feeding a tying strand 35 from said free end during the describing of the loop.

2. In a box strapping machine, means for supporting a box with one end projecting beyond the support, a swingably supported extensible 40 member movable across the face of the projecting box end in a plane parallel thereto, means for guiding the free end of the extensible member in the path of a loop corresponding substantially to the shape of the box and a feeder for a strand 45 of wire revolvably mounted in the free end of the member and projecting over the box so as to feed the wire therearound.

3. In a box strapping machine, a wire holder having means for securing a wire to one end 50 thereof, means for retracting the holder and a guard adjacent the holder for pushing off the wire when the holder is retracted.

4. In a box strapping machine, a wire holder comprising a cylinder, a plunger movable therein, 55 spring means causing the plunger to normally project beyond the cylinder, the projecting end being formed with an endwise slot for receiving a wire therein, a member movable longitudinally on the plunger and a connection between the member and the plunger causing the plunger to turn for gripping the wire without moving the plunger axially when the member moves through a certain distance in one direction, the said connection being made to retract the plunger into the cylinder for ejecting the wire when the movement of the member is reversed and continued in the opposite direction.

5. In a box strapping machine, a wire holder comprising a cylinder with a slanting upper end, 70 a plunger movable therein, spring means causing the plunger to normally project beyond the cylinder, the projecting end being formed with an endwise slot for receiving a wire therein, a member movable longitudinally on the plunger and a connection between the member and the plunger

causing the plunger to turn for gripping the wire without moving the plunger axially when the member moves through a certain distance in one direction, the said connection being made to retract the plunger into the cylinder for ejecting the wire when the movement of the member is reversed and continued in the opposite direction.

6. In a box strapping machine, a retractile post, means for securing a wire thereto and a collar snugly encircling the post for pushing off 10 the wire when the post is retracted into the collar.

7. In combination, an arm arranged in substantially upright position and having its lower end swingably supported, an element slidable on the 15 arm and extendible therefrom, an angularly-disposed lever having a pivot supporting the same intermediate its ends, a substantially horizontal cylinder having a pivoted connection with the upper lever end, a rod swingably connected to the 20 arm having a piston within the cylinder, means for moving the piston relative to the cylinder in either direction, a link connecting the lower lever end with the slidable element, and a wire-feeder 25 on the slidable element.

8. In a box strapping machine, means for supporting a box with one end projecting beyond the support, a swingably supported extensible member normally disposed entirely below the box when in a position of rest and movable across 30 the face of the projecting box end in a plane parallel thereto, means for guiding the free end of the extensible member in a path corresponding substantially to the shape of the box and a feeder for a strand of wire revolvably in the free 35 end of the member and projecting over the box so as to feed the wire therearound.

9. In combination, an endwise extensible member, means pivoting one end thereof for swinging of the member in a lateral plane, the member being extensible in the plane defined by the swinging of the member, means for actuating the member to cause its free end to describe the path of a loop, and means for feeding a tying strand 45 from said free end during the describing of the loop.

10. In combination, an endwise extensible member, means pivoting one end thereof for swinging of the member in a lateral plane, the member being extensible in the plane defined by 50 the swinging of the member, means for actuating the member to cause its free end to describe the path of a loop, the later means including a guide member for controlling the shape of the loop, and means for feeding a tying strand from said free 55 end during the describing of the loop.

11. In a box strapping machine, means for supporting a box with one end projecting beyond the support and means for guiding a wire around the projecting box end, the latter means including an endwise extensible member mounted for lateral swinging across the face of the projecting box end and an exchangeable guide member co-operating with the extensible member for controlling the path followed by the wire.

12. In a box strapping machine, a rod-like holder having a pair of spaced prongs, mechanical means for introducing a wire between the prongs from one side of the holder, and means for turning the wire holder axially, whereby the wire is 70 wrapped relative to the holder and locked in position.

13. In a box strapping machine, an endwise extensible member having one end thereof pivotally supported, means for guiding the free end 75

- of the member to describe the path of a loop corresponding substantially to the outline of a box, and a wire feeding spout projecting from the free end of the member to feed a wire around the box, 5 the spout being revolvable in the member for turning on an axis paralleling the axis of the pivotal support of the member and having means for yieldingly holding the spout in a predetermined position.
- 10 14. In a box strapping machine, a rotatable post having a slot therein, a movable member having a wire projecting therefrom, the slot being alignable with the projecting wire when the post is turned into a predetermined position, means for 15 moving the member toward the post, whereby the wire is made to enter the slot, and means for turning the post for fastening the wire to the same, the post having a cut-away portion to allow the movable member to pass from one side of the 20 post to the other after the post has been turned for fastening the wire thereto.
15. In combination, an arm arranged in substantially upright position and having its lower end swingably supported, an element slidable on 25 the arm and extendible therefrom, an angularly-disposed lever having a pivot supporting the same intermediate its ends, a substantially horizontal link connecting the upper lever end with the arm, a second link connecting the lower lever end with 30 the slidable element, a wire-feeder on the slidable element, means for extending and contracting the first-named link to move the element relative to the arm and to swing the latter on its pivot, and means for guiding the wire-feeder in a looped 35 path.

16. In a box strapping machine, means for supporting a box, means for anchoring the end of a wire, a swingably mounted arm and an element 5 slidable relative thereto, the slidable element having a wire-feeder thereon for looping a wire around the box, a guide plate having an endless groove, a roller on the slidable element to move the wire-feeder in the path of a loop when the roller travels around the groove, means for moving the roller around the groove, an extension groove communicating with the endless groove to receive the roller, and means for arresting feeding of the wire from the wire-feeder when the roller enters the extension groove, whereby the looped wire is tensioned around the 10 box.

17. In a box strapping machine, means for supporting a box, means for anchoring the end of a wire, a swingably mounted arm and an element 15 slidable relative thereto, the slidable element having a wire-feeder thereon for looping a wire around the box, a guide plate having an endless groove, a roller on the slidable element to move the wire-feeder in the path of a loop when the roller travels around the groove, means for moving the roller around the groove, an extension groove communicating with the endless groove 20 to receive the roller, means for arresting feeding of the wire from the wire-feeder when the roller enters the extension groove, whereby the looped 25 wire is tensioned around the box, and means normally closing the extension groove against entry of the roller.
